COOKING MATERIAL RECEPTACLE AND
SPOON LEVELER

William L. Longan, Dimmitt, Tex., assignor of one-half to E. K. Longan, Wichita Falls, Tex.

Application February 7, 1939, Serial No. 255,122

4 Claims. (Cl. 221—146)

This invention relates to improvements in material storage bins or receptacles and pertains particularly to an improved plural bin receptacle designed for the storage of materials used in cooking.

In the art of cooking, use is constantly made of a variety of ground, granulated or powdered materials such as salt, baking powder, bicarbonate of soda and numerous spices or other condiments, and it frequently occurs that in measuring out these various substances it is necessary to bring out a large number of individual receptacles which in addition to adding to the work involved, adds to the number of items which must be moved about during the preparation of the food. The present invention has for one of its primary objects to provide a compact group of bins or containers all arranged in a single receptacle and provided with a common cover or lid so that the several different materials required in the cooking operation will be readily at hand in one receptacle and easy to obtain when wanted.

Another object of the invention is to provide in association with a material container of the above described character, a novel means for leveling a spoon which has been dipped into any one of the several materials in the container, which leveling means is so arranged with respect to the individual bins of the container or receptacle that there is no possible chance of the materials becoming mixed one with another.

A further object of the invention is to provide a plural bin receptacle having the above described features and provided with a novelly arranged spoon receptacle, the lower part or bottom of which constitutes the leveling means described, and is so designed that it will not only serve as a means for leveling off the contents of the spoon but will operate as a means for mashing or breaking any lumps of material which may be in the spoon as the material is being leveled off.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a view in perspective of the device embodying the present invention, showing the bin cover open.

Fig. 2 is a detailed sectional view illustrating the use of the spoon leveling means.

Referring now more particularly to the drawing, the numeral 1 generally designates a receptacle having a low front wall portion 2 and side walls 3, the forward edges of which are cut to extend rearwardly and upwardly, as indicated at 4, to a point short of the top edges thereof and then extended upwardly and forwardly, as indicated at 5. A top 6 is hingedly attached to the receptacle 1, as shown, and through this top, access may be had to the several bins or compartments in which the interior of the receptacle is divided.

The receptacle here illustrated is shown as having two vertical partition walls 7, each of which extends from the front wall 2 to the back of the receptacle and from the bottom to the top thereof, thus dividing the receptacle into three bins 8, but it is to be understood that the invention is not to be limited to the number of bins shown, as it will be readily obvious that there may be provided a receptacle having a less or greater number of bins without departing from the spirit of the invention.

Disposed within the open area between the edges 4 of the side walls is a spoon trough 9, the back of which is indicated by the numeral 10 and forms an upwardly and forwardly extending front wall which is continued down into the receptacle between the side walls and then merges with the forwardly and downwardly inclined bottom portion 11 of the trough and terminates in the upwardly and forwardly inclined low front wall portion 12. The walls 10 and 12 are slightly divergent upwardly although they may be in parallel relation if desired, but it is important that the bottom wall 11 be inclined downwardly and forwardly as shown, and that the corner formed between the walls 10 and 12 be relatively widely rounded, as indicated at 13, for the purpose hereinafter described.

The partitions 7 extend back from the front wall 2 and are formed to follow the contour of the bottom of the trough 9 and to extend upwardly along the back wall 10 of the trough 9 to the top of the receptacle 1, so that the bins 8, back of the trough 19, are of the same depth as the interior of the receptacle. The front wall 10 of the receptacle, or the back wall of the trough, has secured thereto the latch 14 which 55

is employed for holding the top 6 in closed position. Hingedly attached to the upper part of the front wall 2, as indicated at 15, is a bin and spoon trough cover or lid 16 which, when closed, 5 rests upon the top edges 4 of the side walls and has its free end edge in close proximity to the wall 10 so that it closely covers the trough 9 as well as the bins in which the cooking materials are placed.

10 In the use of the present device, the measuring spoon is kept in the trough 9. Such a spoon is shown in Fig. 2 and indicated by the numeral 17. When material is to be removed from any one of the bins, the bowl of the spoon may be dipped directly into the bin beneath the trough 9 and if 15 it is necessary that the contents of the spoon be leveled, this may be accomplished by extending the spoon back beneath the trough 9 as the material is being dipped up and then as the spoon is withdrawn raising it until the edge comes into contact with the rounded corner 13 of the trough. By withdrawing the spoon outwardly while maintaining this contact with the trough, the inclined bottom 11 of the trough will smooth off the 20 contents of the spoon and will also mash or break any lumps of material which the spoon may have picked up. Thus it will be seen that with a device of the kind herein described, a number of cooking materials may be kept under one cover and 25 that novel means is provided in association with such material cooking means for leveling the measuring spoon with which materials are removed.

Another advantage of the present device 30 resides in the novel formation of the open front thereof whereby when it is placed on a table or other support facing the user, the bins will be in the right position for the user to most easily obtain the contents thereof and to level off the 35 spoon. In other devices having spoon leveling means, such leveling means is usually upon the top of the receptacle and it is, therefore, inconveniently located, whereas in the present device, the leveling means is within the receptacle where 40 the one movement of dipping the material and leveling the same as the spoon is removed suffices.

In the leveling of certain cooking ingredients such as soda, it is very important that the measuring spoon be accurately leveled otherwise the 45 strong leavening action of the soda, if too large a quantity were employed, might spoil the material being prepared and such accurate leveling is more conveniently obtained with the present 50 device than with devices of other types on the market.

I claim:

1. A material receptacle of the character described, comprising a body having a front wall and side walls, said side walls being cut back at a forward and rearward inclination to form a forwardly and downwardly inclined opening, a trough 60 extending across said opening at the rear part thereof, said trough having a forwardly and upwardly inclined back wall constituting a partial front wall for the upper part of the receptacle, the said trough back wall extending downwardly into the receptacle and merging with a bottom wall which terminates in an upwardly extending front wall portion 65 having its edge flush with the said edges of the side wall, the front walls of the trough being spaced from the first mentioned front wall portion of the receptacle, a partition extending rearwardly from said front wall beneath the trough to form bins, and a cover hingedly attached to a wall of the receptacle to overlie said opening and said bins.

2. A material receptacle of the character described, comprising a body having a front wall and side walls, said side walls being cut back at a forward and rearward inclination to form a forwardly and downwardly inclined opening, a trough 70 extending across said opening at the rear part thereof, said trough having a forwardly and upwardly inclined back wall constituting a partial front wall for the upper part of the receptacle, the said trough back wall extending downwardly into the receptacle and merging with a bottom wall which extends forwardly and which terminates in an upwardly extending front wall portion having its edge flush with the said edges of the side wall, the front wall of the trough being spaced from the first mentioned front wall portion of the receptacle, partitions extending rearwardly from said front wall beneath the trough to form bins, a cover hingedly attached to a wall of the receptacle to overlie said opening and said bins.

3. A material receptacle of the character described, comprising a body having a front wall and side walls, said side walls being cut back at a forward and rearward inclination to form a forwardly and downwardly inclined opening, a trough 75 extending across said opening at the rear part thereof, said trough having a forwardly and upwardly inclined back wall constituting a partial front wall for the upper part of the receptacle, the said trough back wall extending downwardly into the receptacle and merging with a bottom wall which extends forwardly and which terminates in an upwardly extending front wall portion having its edge flush with the said edges of the side wall, the front wall of the trough being spaced from the first mentioned front wall portion of the receptacle, partitions extending rearwardly from said front wall beneath the trough to form bins, a cover hingedly attached to a wall of the receptacle to overlie said opening and said bins.

4. A material receptacle of the character described, comprising a container having a front wall and side walls, said side walls being cut back at an upward and rearward inclination from the front wall above the lower edge thereof to form a forwardly and downwardly inclined opening, a trough 80 extending across said opening at the rear upper part thereof, said trough having an upwardly extending and forwardly inclined back wall constituting a partial front wall for the upper part of the receptacle, the said trough back wall extending downwardly into the receptacle and merging with a bottom wall which extends forwardly and which terminates in an upwardly extending front wall portion spaced from the front wall of the receptacle and having its top edge flush with the said edges of the side walls, and a cover hingedly attached to a wall of the receptacle 85 to overlie said opening and the trough.
